US0D1029476S

(12) **United States Design Patent** (10) **Patent No.:** **US D1,029,476 S**
(45) **Date of Patent:** **** Jun. 4, 2024**

(54) **SHOE OUTSOLE BOTTOM**

(71) Applicant: **Skechers U.S.A., Inc. II**, Manhattan Beach, CA (US)
(72) Inventor: **Glen Chang**, Rancho Palos Verdes, CA (US)
(73) Assignee: **Skechers U.S.A., Inc. II**, Manhattan Beach, CA (US)
(**) Term: **15 Years**
(21) Appl. No.: **29/879,072**
(22) Filed: **Jun. 30, 2023**
(51) LOC (14) Cl. **02-04**
(52) U.S. Cl.
USPC **D2/954; D2/951**
(58) **Field of Classification Search**

(57) **CLAIM**

The ornamental design for a shoe outsole bottom, as shown and described.

DESCRIPTION

FIG. 1 is a front perspective view of a shoe outsole bottom in accordance with my new design;

FIG. 2 is a bottom perspective view of the shoe outsole bottom thereof;

FIG. 3 is a front elevation view of the shoe outsole bottom thereof;

FIG. 4 is a rear elevation view of the shoe outsole bottom thereof;

FIG. 5 is a left side elevation view of the shoe outsole bottom thereof;

FIG. 6 is a right side elevation view of the shoe outsole bottom thereof;

FIG. 7 is a top plan view of the shoe outsole bottom thereof; and,

FIG. 8 is a bottom plan view of the shoe outsole bottom thereof.

Broken lines shown in the drawing represent environmental structure of the shoe and portions of the shoe outsole bottom that form no part of the claimed design.

1 Claim, 7 Drawing Sheets
